UNITED STATES PATENT OFFICE.

CHARLES E. THOMPSON, OF LANSINGBURG, NEW YORK.

DESIGN FOR A BRUSH.

SPECIFICATION forming part of Design No. 17,786, dated October 11, 1887.

Application filed July 25, 1887. Serial No. 245,293. Term of patent 7 years.

To all whom it may concern:

Be it known that I, CHARLES E. THOMPSON, a citizen of the United States, residing at the village of Lansingburg, in the county of Rensselaer and State of New York, have invented and produced a new and original Design for Brushes, of which the following is a specification, reference being had to the accompanying drawings, forming a part thereof.

Figure 1 is a side elevation of my newly designed brush. Fig. 2 is a top plan view of same.

A represents a circular brush-head; B, the handle, and C a spur projecting from the farther end of the handle. The handle has the form of a series of connected coils of wire, and

appears to project laterally from one side of the upper part of the head and a little above a horizontal plane when the head is placed in a vertical position, as shown in Fig. 1. 20

I claim—

The design for a brush herein shown and described, the same consisting of a circular head with a lateral projection therefrom in the form of a series of connected wire coils. 25

In testimony whereof I have hereunto set my hand this 22d day of July, 1887.

CHARLES E. THOMPSON.
